UNITED STATES PATENT OFFICE.

JUDSON HARLEY MISKIMEN, OF GLENDALE, MONTANA.

CLOTHES-LIFTER.

1,228,945.

Specification of Letters Patent. Patented June 5, 1917.

Application filed July 31, 1916. Serial No. 112,302.

To all whom it may concern:

Be it known that I, JUDSON H. MISKIMEN, a citizen of the United States, residing at Glendive, in the county of Dawson and State of Montana, have invented certain new and useful Improvements in Clothes-Lifters, of which the following is a specification, reference being had therein to the accompanying drawing.

10 This invention relates to improvements in clothes lifters, one object of the invention being the provision of a clothes lifter, which is so constructed as to permit of the engagement of the wet clothes without danger of 15 tearing or damaging the same.

A further object of the invention is the provision of a safety clothes lifter, the clothes engaging members of which are formed from wire, and provide a plurality 20 of resilient loops anchored in a handle, so that the loops may be readily engaged with or released from the clothes without injuring the fabric.

A still further object of this invention is 25 the provision of a safety clothes lifter which is simple, durable and cheap to manufacture, and which is thoroughly efficient and practical in use.

In the accompanying drawings:—

30 Figure 1 is a perspective view of one form of lifter.

Fig. 2 is a cross section through the handle showing the method of anchoring the loops.

35 Referring to the drawings, and more particularly to Figs. 1 and 2 thereof, the nu-

meral 10 designates the three loops, each of which is made from a single strand of wire and has its terminals 11 placed within the transverse slit or slot 12 of the handle or 40 staff 13, a ferrule 14 surrounding the handle at this point and clamping the ends 15 of the handle tightly upon these terminals 11, which are substantially parallel.

One of the loops is shorter than the others 45 and is curved as at 16, thus providing a safety clothes lifter, by means of which the clothes may be manipulated without being torn.

It will be noted that the ends of the terminals 11 fit or abut against the inner end of 50 the slot formed by the clamping ends 15 and that all of the respective terminals 11 are substantially parallel.

What I claim, as new, is:—

55 A clothes lifter, comprising a staff one end of which is provided with a transverse slot diametrically thereof, a plurality of strands of wire bent to form loops and having the terminals thereof disposed in parallel and seated within the slot with the extreme ends thereof abutting the closed end of the slot, the two outer loops being slightly bent to diverge from the ends of the staff, and the intermediate loop being bent out of 60 plane with the first two loops, and a ferrule 65 surrounding the end of the staff to clamp the terminals of the staff upon the terminals of the loops within the slot.

In testimony whereof I affix my signature. 70

JUDSON HARLEY MISKIMEN.
